Primary Examiner — Robert M Spear*Assistant Examiner* — Marissa J Cash(74) *Attorney, Agent, or Firm* — Kilpatrick Townsend & Stockton LLP(57) **CLAIM**

What is claimed is a design of a vent, as shown and described.

DESCRIPTION

FIG. 1 is a three-quarter top isometric view of a vent of the design of the present invention;

FIG. 2 is a front side view of the vent design of FIG. 1;

FIG. 3 is back side view of the vent design of FIG. 1;

FIG. 4 is a right side view of the vent design of FIG. 1;

FIG. 5 is a left side view of the vent design of FIG. 1;

FIG. 6 is a bottom view of the vent design of FIG. 1;

FIG. 7 is a top plan view of the vent design of FIG. 1; and,

FIG. 8 is a three-quarter bottom isometric view of the vent design of FIG. 1.

Broken lines in the Figures form no part of the claimed design.
